ATTYS.

UNITED STATES PATENT OFFICE.

ARTHUR W. JONES, OF BOSTON, MASSACHUSETTS, ASSIGNOR TO THE THOMSON-HOUSTON ELECTRIC COMPANY, OF CONNECTICUT.

MULTIPLE-FUSE CUT-OUT.

SPECIFICATION forming part of Letters Patent No. 450,159, dated April 14, 1891.

Application filed December 6, 1890. Serial No. 373,783. (No model.)

To all whom it may concern:

Be it known that I, ARTHUR W. JONES, a citizen of the United States, residing at Boston, county of Suffolk, and State of Massachusetts, have invented a certain new and useful Improvement in Multiple-Fuse Cut-Outs, of which the following is a specification.

My invention relates to a multiple-fuse cut-out box in which are combined a series of fusible cut-out strips so arranged in relation to movable and fixed contacts that the fusible strips may be successively brought into circuit as they are required.

My invention consists in constructing such a multiple-fuse cut-out with a pair of stationary contacts and a series of movable contacts adapted to be brought successively in contact with the stationary contacts and a continuous strip of fusible metal secured to the said series of movable contacts so that the said continuous strip is divided by said series of contacts into a series of electrically separate fuses.

My invention further consists in combining with a multiple fuse having a pair of stationary contacts and a series of movable contacts with interconnecting safety-fuses of a blow-out magnet or other means for breaking the arc located between or in proximity to the said stationary contacts.

In the accompanying drawings, Figure 1 represents a plan view of my improved cut-out box; Fig. 2, a section of the same, taken on the line 2-2 of Fig. 1. Fig. 3 is a detail section showing the construction of the stationary contacts with one of the movable contacts bearing thereon.

A represents a box which is preferably made of iron, and may be lined with fire-proof insulating material *a*, such as asbestos, plaster, or mica.

B B are the stationary contacts connected by the wires C with outside binding-posts D D.

E represents a continuous strip of fuse-wire, and F a series of spring-clips in which said fuse-wire may be easily clamped. The clips are made of two pieces of spring copper or brass and are mounted upon spokes G of metal, which are secured to a hub H of insulating material rotatable upon or with a spindle I. The spokes G form movable contacts

adapted to successively connect with the stationary contacts D D, the space between two adjacent spokes being equal to the distance between the stationary contacts.

55

It will be seen that when the fuse-wire is in place and a pair of the movable contacts are brought into connection with the stationary contacts that part of the fuse-wire between such contacts will be in circuit, and in case of an undue increase in current this part, and this part only, of the fuse-wire will be ruptured. It is only necessary then to move the fuse-carrier, so as to bring the next pair of contacts thereupon into connection 65 with the stationary contacts in order to throw a new section of fuse into circuit. By using a continuous strip of fuse-wire for making two or more electrically separate fuses I am enabled to make the operation of renewing 70 the fuse much simpler and easier, as heretofore such fuses have been not only electrically but mechanically separate. I prefer to make the clips with a slot at *e*, so that by the insertion of a sharp-pointed tool the ends of 75 the fuse-wire that remain after the fuse has "blown" may be easily ejected through the clips.

K represents an electro-magnet connected in the main circuit, as shown. This magnet 80 is located so as to present its pole to that part of the fuse which is in circuit, so that it will act to rupture the arc that is formed upon the blowing of the fuse. The spindle I projects through the ends, as shown, and has a 85 square end at *i*, over which a key L is adapted to fit for the purpose of turning the fuse-carrier from the outside.

When all the sections of the fuse-wire are used up, there will be found a small piece remaining in each of the clips. These may be easily ejected by a nail or other pointed tool, and a new strip of fuse-wire may then be strung through the clips, and the apparatus thus put in condition for additional service. 90

What I claim as new, and desire to secure by Letters Patent, is—

1. A safety-fuse apparatus comprising a pair of fixed contacts, a fuse-carrier having movable contacts co-operating with said fixed contacts and provided with a manual operating device, and a continuous strip or wire of 100

fusible material engaged in sections by said movable contacts, so as to bring successive portions of said wire into connection with said fixed contacts.

5. 2. A movable fuse apparatus comprising a rotatable block provided with a handle rotating the same, a series of combined contacts and clips on said block, a continuous fusible wire wound around said block and held in 10 said clips, and a pair of fixed contacts co-operating with any two of said movable contacts.

3. A multiple-fuse apparatus in which are combined a pair of stationary contacts, a series of movable contacts, and a continuous strip of fusible metal attached to the said movable contacts, so as to be divided by said movable contacts into two or more independent sections, the space between any pair of 20 adjacent movable contacts being equal to the space between the stationary contacts.

4. The combination, in a multiple fuse, of

a pair of stationary contacts, and a series of movable contacts provided with spring-clips, with a continuous strip of fusible metal 25 clamped within the spring-clips and making electrical connection between the series of movable contacts.

5. The combination, in a multiple-fuse apparatus, of a pair of stationary contacts, a series of movable contacts adapted to make successive connections with the stationary contacts in pairs, a series of fusible connections between said movable contacts, and a device for rupturing the arc located between or adjacent to the stationary contacts, so as to operate only upon that section of the fuse which is in circuit. 30 35

In testimony whereof I have hereto set my hand this 4th day of December, 1890.

ARTHUR W. JONES.
